B. R. H. LYON

VENTILATOR

Filed July 20, 1925

INVENTOR

D.R.HLYON
BY MURRAY LEE
ATTORNEY

UNITED STATES PATENT OFFICE.

BABET R. HAND LYON, OF CHICAGO, ILLINOIS, ASSIGNOR OF ONE-HALF TO DE WITT TAYLOR LYON, OF CHICAGO, ILLINOIS.

VENTILATOR.

Application filed July 20, 1925. Serial No. 44,834.

My invention relates to improvements in ventilators, and it consists in the combinations, constructions, and arrangements herein described and claimed.

5 The standard ventilator for theaters and the like projects quite a distance above the surface of the floor and it is therefore necessary to use what is called a thimble to make an opening in the floor before the concrete has hardened. This thimble lies flush with the surface of the floor so as to permit trucks and the like to be moved across the surface of the floor without in any way damaging the thimbles.

10 15 After the concrete has set and after all necessary trucking across the surface of the floor has been accomplished, the thimbles are removed and the standard ventilator is inserted in the opening in the concrete made by the thimbles.

The principal object of my invention is to provide a ventilator that may be disposed in place before the concrete is poured, thus doing away with the necessity of thimbles.

20 25 To this end I have provided the ventilator with a very narrow flange that projects above the surface of the floor whereby the necessary trucking across the surface of the floor may be done without in any way affecting the ventilator. After this trucking has been done, the remaining parts of the ventilator are secured to the part already embedded in the cement or concrete. In this way I provide a ventilator which cuts down 30 35 the amount of labor necessary to install the ventilator, to a minimum.

A further object of my invention is to provide a ventilator of the character described which is adjustable so as to regulate the flow of air through the ventilator, the means for adjusting the ventilator being adapted to lock the ventilator in adjusted position.

40 45 A further object of my invention is to provide a ventilator of the character described in which the air is discharged under the adjoining seats instead of against the feet and ankles of people occupying the seat under which the ventilator is disposed.

50 Other objects and advantages will appear in the following specification, and the novel features of the invention will be particularly pointed out in the appended claims.

My invention is illustrated in the accom-

panying drawings, forming part of this application, in which—

Figure 1 is a plan view, and

Figure 2 is a section along the line 2—2 of Figure 1.

In carrying out my invention I provide a ventilator having a body portion A, with a cylindrical shaped portion 1, an outwardly extending flange 2 adapted to lie flush with the upper surface 3 of a concrete floor 4, and an upwardly extending flange 5. The flange 5 is very narrow in width and therefore projects only a slight distance above the surface 3. The body portion A is disposed in place on the flooring, not shown, before the concrete 4 is poured. A wooden disc, not shown, is disposed in the recess provided by the flanges 2 and 5 and prevents the concrete from flowing into the cylinder 1. The portion B of the ventilator is attached to the portion A after all necessary trucking across the surface 3 of the floor is accomplished.

As heretofore stated, the flange 5 is very narrow and therefore permits trucks to be moved across the surface 3 and floor without in any way interfering with the body portion A. It should be noted that the body portion A is a shell having a wall thickness of approximately one-eighth of an inch. This shell is strong enough to withstand the weight of a truck in case a truck should pass thereover. Furthermore, the flange 5 is of such a narrow width that it will permit the trucks to pass over the flange. In the standard ventilators the portion disposed in the concrete extends to such a height above the surface of the cement or concrete that it interferes with the necessary trucking. It has therefore been necessary to insert thimbles in the concrete and leave these thimbles in place until the time came for mounting the ventilators in the flooring. With the present device, however, this extra labor is entirely done away with, and furthermore, there is no necessity for providing thimbles. This is a vital feature of the device and is a distant improvement over standard ventilators.

The flange 5 is also provided with means for securing the portion B of the ventilator to the portion A. In the present form of the device, this part of the ventilator consists of a semi-circular cover 6 that is secured

to the flange 5 by means of screws or the like. Each end of the cover 6 is secured in place by two screws so as to rigidly secure the cover to the flange. The cover is cut 5 away so as to provide openings 8 and 9 between the cover and the flange 5. These openings permit the air to flow out into the room of the theater.

10 The means for controlling the flow of air through the openings 8 and 9 consists in semi-circular shaped doors 10 and 11. In the present form of the device these doors are pivotally secured to the same screws 7 that secure the cover to the flange 5. I have 15 shown both doors in closed position in Figure 2, but of course in operation either one or both of these doors will be opened partially or will be disposed in entirely open position.

20 The doors 10 and 11 may be adjusted by any means and I have shown for this purpose a series of threaded openings 12 in the cover 6 and a second series of threaded openings 13 also in the cover 6. The doors 10 and 11 carry screws 14 and 15 that are 25 adapted to enter any one of the threaded openings in the series 12 and 13 respectively.

From the foregoing description of the various parts of the device, the operation thereof may be readily understood. The doors 10 30 and 11 are moved with respect to the cover 6 until final adjustment of the ventilator is reached and then the screws 14 and 15 securely lock the doors to the cover. It should be noted that the doors 10 and 11 are disposed 35 in such a position with respect to the seats in the theater as to direct the air under adjoining seats instead of against the feet and ankles of the person occupying the seat under which the ventilator is disposed. In this way all 40 drafts are eliminated. If desired, the cover 6 may be shaped so as to have a cross section through the cover oval in shape or rectangular in shape instead of circular as is the case in the present instance. The device is 45 extremely simple in construction and provides a novel means for entirely doing away with the necessity of providing temporary thimbles. In Figure 2 I show the doors 10

and 11 as being movable over the outer surface of the cover 6. The air in flowing 50 through the ventilator is directed by the shape of the cover 6 toward the openings 8 and 9. The speed of the air through the openings 8 and 9 will tend to prevent the air from reversing in its movement and passing through the space between the doors and the cover if such a space should exist. If the doors were movable on the inside of the cover, the air would flow through the spaces 60 between the doors and cover, if such spaces in fact did exist and would thus defeat the purpose of the invention. In this way I provide a simple means for overcoming any irregularities of shape in the ventilator. 65

I claim:

1. A ventilator comprising a body portion having an unobstructed passageway therethrough, and being provided with a laterally extending flange portion at one end, and a rim at the edges of said flange portion, a cover member rigidly secured to said rim and having arc-shaped end portions spaced from said rim and arc-shaped doors hinged to said rim and arranged to be 70 swung with respect to the end portions of 75 said cover member to vary the effective opening between said cover member and said rim.

2. A ventilator comprising a body portion having an unobstructed passageway there- 80 through, and being provided with a laterally extending flange portion at one end, and a rim at the edges of said flange portion, a cover member rigidly secured to said rim and having arc-shaped end portions 85 spaced from said rim and arc-shaped doors hinged to said rim and arranged to be swung with respect to the end portions of said cover member to vary the effective opening be- 90 tween said cover member and said rim, the curvature of said doors conforming to that of the arc-shaped ends, and means for securing said doors to said ends at various positions.

BABET R. HAND LYON.
